UNITED STATES PATENT OFFICE.

JOSEPH W. DROLL, OF CHICAGO, ILLINOIS, ASSIGNOR TO DROLL PATENTS CORPORATION OF DELAWARE, A CORPORATION OF DELAWARE.

MATTRESS-BEATING MACHINE.

Application filed May 28, 1923. Serial No. 642,060.

To all whom it may concern:

Be it known that I, JOSEPH W. DROLL, a citizen of the United States, residing in the city of Chicago and county of Cook and State of Illinois, have invented a new and useful Improvement in a Mattress-Beating Machine, of which the following is a specification.

My invention relates to improvements in mattress beating machines wherein a resilient mattress support operates in conjunction with beating elements on each side thereof to engage and beat sides of said mattress simultaneously.

15 The primary object of the present invention is to provide a new and improved mattress machine;

Another object is to provide a new and improved device of the character described that shall be adapted to beat the stuffing within a mattress uniformly into the corners and edges thereof;

A further object is to provide improved means for resiliently supporting a mattress 25 between a pair of beating elements in such a manner that both sides of said mattress may be engaged and beaten simultaneously;

A still further object is to provide a new and improved device of the type set forth having a rotatable mattress support arranged to rotate a mattress between beating elements whereby the stuffing within said mattress may be forced in various directions and into the sides and corners of the 35 said mattress;

A further object is to provide a mattress 40 machine having improved lofting means for lofting the mattress stuffing in the center of said mattress.

It is also an object to provide an improved mattress beating machine having beating elements arranged to rapidly and successively corrugate a mattress to facilitate a uniform distribution of stuffing within said 45 mattress;

Another object is to provide a pair of beating elements arranged to beat both sides of a mattress simultaneously and improved means for operating either beating element independently of the other and also for adjusting one of said beating elements relatively to the mattress.

Another object is to provide a mattress

beating machine comprising a pair of beating elements arranged to engage both sides of a mattress simultaneously and a slidably mounted resilient support arranged to move a mattress into and out of operative relation to said beating elements; and also to provide mechanism or means for preventing the operation of one of the beating elements while the mattress is being so moved and to prevent the introduction or removal of said mattress while being engaged by one of said beating elements.

A still further object is to provide a stripping mechanism to prevent mattresses built of cheaper grades of ticking from winding around the bars of the beating elements during the beating process.

I accomplish these and other objects by means of the preferred form of the device disclosed in the drawings forming a part of the present specification wherein like characters of reference are used to designate similar parts throughout the said specification and drawings, and in which

Fig. 1 is a broken front elevation of my improved mattress beating machine, disclosing a mattress in operative position relatively to the beating elements;

Fig. 2 is a partly broken right hand elevation of Fig. 1;

Fig. 3 is a transverse vertical sectional view taken on line 3—3 of Fig. 1 in the direction indicated;

Fig. 4 is a broken plan view of Fig. 1;

Fig. 5 is a broken plan view of the mattress supporting table and the bars of the upper beating elements; and disclosing in full and dotted lines the various positions assumed by the mattress relatively to the said beating elements, during rotation of the mattress support;

Fig. 6 is a broken detailed view of the upper beater frame;

Fig. 7 is a broken detailed view disclosing the manner in which one corner of the upper beating element frame is mounted upon the elevator rods;

Fig. 8 is a front elevation of Fig. 7 including the gears for rotating said rod;

Fig. 9 is a detailed view of one of the beating elements;

Fig. 10 is an enlarged broken detail view of the manner in which one portion of the

mattress supporting frame is rotatably mounted;

Fig. 11 is a broken detailed view disclosing the means for locking the lower beating elements against operation while the sliding mattress support is being moved, or is out of operative position, and for preventing withdrawal of said support while the said lower beating element is in operation.

10 Fig. 12 is an enlarged broken elevation of one side of the automatic reversing mechanism for elevating and lowering the upper beating elements;

Fig. 13 is a broken plan view, partly in 15 section, of Fig. 12; and

Fig. 14 is an elevation of the opposite side of said mechanism.

Referring to the drawings the numeral 1 is used to designate the corner angles or 20 members of a suitable frame having front and rear horizontal bars 2 and also pairs of front and rear vertically disposed channels 3. Extending from front to rear of the frame and having their ends rigidly 25 secured to the vertically disposed channels 3 are two pairs of parallel angles 4 and between each pair of angles 4 I have pivotally mounted a plurality of rockers 6 having arms 7 connected thereto and offset to- 30 wards the center of the main frame, as disclosed in Fig. 1 of the drawings. The rockers 6 and arms 7 connected thereto are ar- 35 ranged in opposite pairs each pair of said arms being connected to a transversely ar- ranged rod 8 which forms the beating ele- 40 ment. When these arms 7 are moved to the uppermost position where the rods 8 engage the lower side of a mattress 9, hereinafter more fully described, the said rods 8 or 45 beating elements are equally spaced.

The rockers 6 are connected by means of suitable links 11 to crank levers 12 also pivotally mounted between the angles 4 and 50 are connected pivotally to stems of cam straps 14 rotatably mounted upon cams 16 on a lower power shaft 17 whereby ro- 55 tation of said shaft 17 will cause said cams 16 to rock the rockers 6, through the medium of the links 11; and thereby impart a reciprocating movement to the arms 7 and rods or beating elements 8 on the free ends 60 of said arms 7.

The ends of the rods 8 are curved to prevent damage to the ticking of the mattress 55 9 or to the resilient mattress support hereinafter more fully described.

Also extending from the front to the rear 60 of the main frame I have provided a second pair of angles 18 resting upon and rigidly secured to the horizontal members 2 herein- before described, to which angles 18 I have connected what I term transverse lofting bars 19, said bars 19 being arranged alter- 65 nately with the bars or beating elements 8 when said bars 8 are in their upper most

positions, the front and rear bars 19 being preferably straight and the succeeding bars 19 each being a little more arcuate or curved toward the center of the machine, the innermost bars being more greatly curved or ar- 70 cuate than the intermediate bars, so that the greatest distance between said bars and the mattress 9 directly over them will be greatest at the approximate center of said mattress 9, as disclosed in Figs. 1 and 3 of the draw- 75 ings, the purpose of which will hereinafter be more fully set forth.

Rollers 21 are mounted upon the outer 80 sides of the angles 18 in order to provide suitable bearings for slidably supporting the lower frame 22 of a circular mattress sup- 85 port 23, said mattress support 23 being rotatably mounted upon the frame 22 by means of suitable rollers 24 mounted upon the said frame 22 and rotatably engaging and sup- 90 porting the inwardly turned flanges of the mattress support 23 one of which rollers is disclosed in Fig. 10 of the drawings.

The resilient circular mattress support 23 is provided with interlaced webs 26 which 95 are in turn secured at their opposite ends to the circular mattress support 23 by means of suitable springs 27, as disclosed in Figs. 3, 4 and 5 of the drawings. By means of 100 this rotatable circular resilient mattress sup- 105 port a mattress 9 may be supported above the lower beating elements or rods 8 and as said rods are reciprocated and strike against the lower surfaces of the webs 26 the blow will be imparted to the bottom of the mat- 110 tress 9 upon said webbing 26, and as said webbing is flexible and resilient it will be the same, in effect as if the bars 8 struck the lower surface of the mattress 9 itself.

The mattress support 23 is moved inward- 115 ly until the rear end thereof strikes a stop pin 28 which will position the mattress 9 directly in correct operative position rela- 120 tively to the beating elements.

The power shaft 17 is rotatably mounted 110 within suitable bearings 31 and is provided at one end with a female clutch member 32 arranged to be engaged and rotated by means of a male clutch member 33 on a shaft 36 115 also mounted within a suitable bearing 37 and having a flywheel driving pulley 38 on the end thereof, as disclosed in Fig. 2 120 of the drawings.

The male clutch member 33 is operated 120 to engage and disengage the female clutch member 32 by means of the usual lever 41 which extends forwardly and projects be- 125 yond the horizontal frame member 2 at the extreme right hand end of the front of the machine.

The right hand channel of the lower por- 125 tion of the supporting frame 22 is provided with a spline or rod 42 having a projection 43 on the rear or inner end thereof. A bell crank latch 44 is pivotally mounted upon 130

the horizontal frame member 2 and is arranged with a vertical portion 46 arranged to be moved in front of the front end of the rod 42 by the clutch lever 41 when the same is actuated to connect the clutch members 32 and 33 and thereby lock the mattress support 23 in operative relation to the beating elements while in operation, by preventing the withdrawal of said supporting frame 22.

When the lever 41 is actuated to disconnect the clutch members 32 and 33 and thereby prevent further operation of the lower beating elements or rods 8 the vertical portion 46 of the latch 44 is moved away from in front of the front end of the rod 42, thereby unlocking or releasing the slideable frame 22 of the mattress support 23 to permit withdrawal thereof, by means of a suitable spring 48, said movement of said latch being permitted by a notch 47 in the latch 44 which notch 47 engages the off or outer side of the lever 41.

As the sliding frame 22 is withdrawn from operative relation to the beater elements 8 the side of the rod 42 engages the vertical portion 46 of the latch 44 and thereby prevents a movement of said latch 44 which will permit the lever 41 to be actuated to again connect the clutch members 32 and 33 and thereby preventing operation of the beaters while said support is withdrawn from operative relation to said beating elements.

From the foregoing it is evident that the mattress support 23 cannot be withdrawn while the clutch 32, 33 is engaged to operate the beating elements 8 and also that said beating elements cannot be operated while the support is withdrawn.

Arranged upon each corner of the main frame or on the corner angles 1 thereof I have provided vertically disposed rotatable threaded rods 51 which rods 51 are engaged by the corners of a vertically movable frame 52 provided with two pairs of parallel angles 53 similar to the angles 4 which support the lower rockers 6 and arms 7 with their beating elements or rods 8.

Mounted between the angles 53 are similar rockers 54 also having inwardly offset arms 56, each pair of arms connected to and operating a second set of beating elements or rods 57, thereby providing a pair of upper and lower beating elements.

The rods 57 of the upper beating elements are arranged alternately with the rods 8 of the lower beating element so that when both upper and lower beating elements are engaging opposite sides of the mattress 9 said mattress will assume a corrugated shape as disclosed in Fig. 3 of the drawings, and the upper beating elements 57 will be directly over and opposite the lofting rods 19 which are arranged below or on the opposite side 65 of the mattress.

The rockers 54 are connected by means of links 59 to cranks also pivotally mounted between the angles 53 and actuated by suitable cam straps 62 mounted upon cams 63 secured to and rotated by an upper shaft 70 64 mounted within suitable bearings 66 on the vertically movable frame 52. The shaft 64 is also provided with a male clutch member 67 which engages a female clutch member 68 mounted upon an aligned shaft 69 75 mounted within a suitable bearing 71, said shaft 64 being also provided with a bevel gear 72 meshing with a similar bevel gear 73 slidably mounted upon a vertically disposed shaft 74 which is rotatably mounted upon one end of the main frame and in the approximate center thereof, as disclosed in Figs. 2 and 3 of the drawings. The lower end of the shaft 74 is provided with a bevel gear 76 which meshes with a similar 85 gear 77 on the power shaft 36 hereinbefore mentioned.

The clutch member 67 is operated to engage and disengage the clutch member 68 by means of an operating lever 78 whose outer end rests within a suitable support 79 and whose inner end is connected by means of a link 81 with a lever 82 connected with said male clutch member 67 whereby the upper beating elements may be operated independently of the lower beating elements.

The vertical shaft is also provided at its upper end with a bevel gear 83 which meshes with two bevel gears 84 and 86 which are loosely mounted upon a horizontally disposed shaft 85, thereby rotating said gears 84 and 86 in opposite directions, said gears 84 and 86 being provided with clutch portions 87 and 88 arranged to engage with clutch collars 89 and 91 respectively, which are slidably keyed to horizontally disposed shaft 85, as disclosed in Figs. 3, 12 and 13 of the drawings.

A shifting rod 92 is slidably mounted to the main frame of the machine and is provided with connections 93 to the clutch collars 89 and 91, said shift rod 92 being also provided with stops 93' and 94 which are arranged to be engaged by levers 95 and pivotally mounted on said frame and held against stops 97 and 98 by means of suitable springs 99 to normally retain both of said clutch collars 89 and 91 in a neutral or disengaging position.

The shift rod 92 extends forwardly to the front of the machine and is pivotally connected with a bell crank 101, as disclosed in Figs. 1 and 3 of the drawings, and to the bell crank 101 I have connected a vertically disposed rod 102 having stops 103 and 104 thereon which are arranged to be engaged by an actuating arm 105 mounted upon the vertically movable upper beating frame 52 as disclosed in Figs. 2 and 3 of the drawings, for the purpose of stopping 130

further movement of the said vertically movable frame 52, in a manner and for a purpose hereinafter more fully set forth.

The vertical rod 102 is connected at its lower end with a pivotally mounted lever 106 provided with a projecting handle 107.

At each end of the horizontal shaft 85 there are bevel gears 109 which mesh with bevel gears 111 at the upper ends of the adjacent vertically disposed threaded rods 51 rotatably mounted within the corner angles 1 of the main frame, and also with bevel gears 112 on front and rear horizontally disposed shafts 114 which are suitably and rotatably mounted within suitable bearings, said shafts extending to the opposite corners of the machine.

The bevel gears 111 and 112 are of the same diameter but of a smaller diameter than the gears 109 whereby both of said gears may be rotated at the same speed and from the same gear 109 on the shaft 85.

The opposite ends of the shaft 114 are each provided with suitable bevel gears 116 which mesh with similar gears 117 on the upper ends of the adjacent vertically disposed threaded rods 51 which elevate and lower the upper beating frame 52.

In order to strip the mattress 9 from the upper beating elements when a thin mattress of inexpensive ticking is being beaten, I have provided strippers which are in the form of parallel rods 121 arranged between and alternately with the upper beating rods 51 or elements 57 so that when the said mattress is being beaten the strippers will prevent the rebound of the mattress from coiling or twining around the said upper beating elements 57.

These stripping rods 121 are depended from the frame 52 and extend a sufficient distance beyond the ends of the upper beating elements 57 to clear the same.

In operation the support 22, with its resilient rotatable portion 23 is slidably moved outwardly toward the front of the machine as disclosed in dotted lines in Fig. 4 of the drawings and the mattress 9 is placed thereon and approximately within the center of said support 23 as disclosed in full lines in Fig. 5 of the drawings, the outward movement of the supports 22 and 23 being limited by the extended portion 43 of the rod 42 mounted upon the side of the frame or support 22 as hereinbefore described.

While the support 22 is in an outward or inoperative position the rod 42 on the side thereof will prevent the latch 44 and the notch 47 therein from releasing the clutch operating lever 41 so that the lower beating elements cannot be operated while the said support is extended.

When, however, the support 22 is moved inwardly to an operative position and

against the stop 28, the latch 44 may be moved to release the lever 41 so that the lower beating elements may be operated.

By moving the lever 106 through the medium of its projection 107 the shifting rods 102 and 92 are actuated to move the clutch collar 89 into engagement with the clutch portion 87 of the gear 84 and thereby rotate the shaft 85, and the various and several connecting shafts and gears to rotate the vertically disposed threaded rods in a direction which will lower the upper beating element frame 52 until it has attained the desired elevation with respect to the mattress 9 upon the resilient rotatable support 23.

Should the operator inadvertently neglect to release the lowering mechanism when the frame has reached the required level, the bracket 105 on the frame 52 will engage the lower stop 104 on the vertically disposed shift rod 102 and thereby move the same downwardly to disengage the clutch collar 89 from the clutch member 87 of the gear 84 and thereby automatically stop the said frame 52.

When the shift rod 102 is moved upward to shift the clutch collar 91 into engagement with the clutch portion 88 of the gear 85 the bracket 105 will likewise engage the upper stop 103 on said rod 102 before the limit of movement of said frame 52 is reached and thereby actuate said rod 102 to disengage the said clutch collar 91 from the clutch portion 88 of the gear 86.

When either collar 89 or 91 is thus disengaged, the tension of the springs 99 will operate to hold the levers 95 and 96 against the stops 97 and 98 respectively, on the main frame and thereby engage the stops or pins 93 and 94 of the shifting rod 92 and hold them in neutral or disengaged position, to prevent further rotation of the shaft 85 and thereby prevent further movement of the frame 52.

When the upper beating elements have been moved to the correct position relatively to the mattress 9 the clutch levers 41 and 78 are moved to cause their respective clutch members to engage and rotate the shafts 17 and 64 and thereby actuate the upper and lower beating elements 57 and 8 respectively to reciprocate and deliver a succession of rapid blows to the mattress 9 and on opposite sides thereof and at alternate points on said opposite sides, thereby rapidly corrugating the mattress as disclosed in Fig. 3 of the drawings, which operation will uniformly distribute the stuffing within the mattress. As these blows or strokes are not vertical or lateral to the mattress 9 but move arcuately it is evident that said blows will tend to move the stuffing within the mattress and as the rotatable resilient support is rotated the position of the mattress 9 thereon

is changed relatively to the direction and position of said strokes until a uniform distribution of stuffing within the mattress has been effected.

5 After a uniform distribution has been thus effected, the lever 41 is moved to disengage the clutch member 33 from the clutch member 32 which rotates the lower shaft 17, thereby preventing further operation of the 10 lower beating elements 8.

This cessation is caused at a point where the lower beating elements 8 are at their lowest position so that said beating elements 8 will not interfere with the arcuate lofting 15 rods or support 19 when the frame 22 is finally withdrawn.

As the upper beating elements 57 continue to operate the mattress 9 is pressed downward by said elements 57 until the 20 mattress comes into contact with said lofting rods 19 which are positioned directly opposite and on the underside of said mattress 9.

As the said lofting rods 19 are arcuate and 25 so positioned that the greatest distance between said rods and the flexible bottom of the supporting frame 23 is at the approximate center of said frame 23 and the mattress 9 thereon, it is obvious that when the 30 pressure of the upper beating elements is withdrawn, the resulting rebound imparted to the mattress 9 by the flexible webs 26 and springs 27 attached thereto will be greater at the center of said mattress 9 than at other 35 portions thereof, with the result that the stuffing within the mattress 9 will be lofted toward the center of said mattress.

This is a desired condition in mattresses as more stuffing is required at the center than 40 at other portions thereof.

The clutch lever 78 is then actuated to disengage the upper beating elements from the power, the lever 106 is actuated to raise the frame 52 upwardly away from the mattress 9, and the support 22 is moved to withdraw the mattress 9 from between the beating 45 elements.

Having thus described my invention what I claim as new and desire to secure by Let- 50 ters Patent is—

1. A mattress beating machine comprising upper and lower beating elements; and means for suspending a mattress between said elements whereby both sides of said 55 mattress may be engaged simultaneously by said beating elements.

2. A mattress beating machine comprising upper and lower beating elements; and resilient means for resiliently supporting a 60 mattress between said elements whereby both sides of said mattress may be engaged by said beating elements.

3. A mattress beating machine comprising a pair of beating elements; and resilient 65 means for resiliently supporting a mattress

between said elements whereby both sides of said mattress may be engaged by said elements simultaneously.

4. A mattress beating machine comprising a pair of beating elements; and means for supporting a mattress between said elements whereby both sides of said mattress may be engaged by said elements simultaneously; and means for operating the beating elements independently of each other to engage the mattress. 75

5. A mattress beating machine comprising a pair of beating elements; and means for supporting a mattress between said elements whereby both sides of said mattress may be engaged by said elements simultaneously; and means for adjusting one of the beating elements relatively to the mattress. 80

6. A mattress beating machine comprising a pair of beating elements; and means for rotatably supporting a mattress between said elements whereby different portions of said mattress may be exposed to and engaged by said beating elements. 85

7. A mattress beating machine comprising a pair of beating elements; and means for slidably supporting a mattress between said elements whereby the insertion and withdrawal of said mattress from said elements may be facilitated. 90

8. A mattress beating machine comprising upper and lower beating elements; and a resilient support slidably and rotatably mounted between the beating elements and arranged to support a mattress between said 100 beating elements to facilitate introduction and withdrawal of a mattress to and from an operative position relatively to said beating elements whereby various portions of both sides of said mattress may be exposed to said beating elements. 105

9. A mattress beating machine comprising a support arranged to resiliently support a mattress to simultaneously expose both sides thereof to the action of beating elements; a stationary beating element arranged to engage and beat one surface of said mattress; and a second beating element arranged to be moved relatively to said mattress to engage and disengage the same 115 and to beat the opposite side thereof.

10. A mattress beating machine comprising a resilient support arranged to resiliently support a mattress; and upper and lower beating elements arranged above and below 120 said mattress support and arranged to engage and beat both sides of said mattress simultaneously, one of said beating elements being adjustable relatively to the mattress.

11. A mattress beating machine comprising a rotatable resilient mattress support arranged to resiliently support a mattress to expose both sides thereof to the action of beating elements; and upper and lower 125 beating elements arranged to engage and 130

beat both sides of said mattress simultaneously; and means for operating either beating element independently of the other.

12. A mattress beating machine comprising a resilient mattress support arranged to support a mattress to expose both sides thereof to the action of beating elements; independently operable beating elements arranged on both sides of said mattress and 10 arranged to engage and beat both sides of said mattress simultaneously, said beating elements comprising a plurality of parallel rods; and stripping means for stripping the mattress from said rods during the beating 15 process.

13. A mattress beating machine comprising upper and lower beating elements; means for resiliently supporting a mattress between said elements to expose both sides 20 thereof to the action of said beating elements simultaneously; means for operating either beating elements independently of the other; and lofting means arranged to support the mattress when the upper beating 25 element only is operated whereby lofting of said mattress may be accomplished.

14. A mattress beating machine comprising upper and lower beating elements; means for resiliently and rotatably supporting 30 a mattress between said beating elements whereby various portions of both sides of a mattress may be exposed to the action of said beating elements simultaneously; means for adjusting one of said beating elements 35 relatively to the mattress; means for operating either beating element independently of the other; and lofting means arranged to support the under side of the mattress when the upper beating element only is operating 40 whereby said mattress may be lofted.

15. A mattress beating machine comprising a pair of independently operable beating elements arranged to engage and beat both sides of a mattress simultaneously; 45 means for resiliently supporting a mattress between said beating elements; and lofting means for lofting the mattress when only one of said beating elements is engaging said mattress.

16. A mattress beating machine comprising a pair of beating elements arranged to engage and beat both sides of a mattress simultaneously; resilient means for supporting a mattress between said beating elements 55 whereby both sides of said mattress may be engaged and beaten by said elements; means for operating either beating element independently of the other; and lofting means arranged to support one side of the mattress 60 when the beating element on the other side thereof is being actuated.

17. A mattress beating machine comprising upper and lower beating elements; resilient supporting means arranged to support a 65 mattress between said elements whereby

both sides of said mattress may be engaged and beaten simultaneously; means for operating either one of the beating elements independently of the other; and lofting means arranged below the mattress and arranged 70 to support and loft the said mattress when the upper beating element only is being operated.

18. A mattress beating machine comprising upper and lower beating elements; resilient supporting means arranged to support a mattress between said elements whereby both sides of said mattress may be engaged and beaten simultaneously; means for operating either one of the beating elements independently of the other; and lofting means arranged below the mattress and arranged 75 to support and loft the said mattress when the upper beating element only is being operated; and stripping means arranged to strip the mattress from said upper beating 80 elements.

19. A mattress beating machine comprising upper and lower beating elements; a 85 slidable support arranged to resiliently support a mattress between said beating elements to expose both sides thereof to said beating elements simultaneously and to move said mattress between and away from said beating elements; means for operating either of the beating elements independently of the other; means for moving the upper beating elements relatively to the mattress; and means for preventing operation of the lower beating element while the slidable support is out of operative position relatively to the lower beating element.

20. The combination with a mattress beating machine comprising beating elements, of a 90 slidable support arranged to move a mattress into and out of operative relation with said beating elements; and means for preventing operation of said beating elements to prevent engagement of the same with the mattress while the latter is being moved into or out of said operative relation.

21. A mattress beating machine comprising a lower stationary beating element; a 95 vertically movable upper beating element; a sliding resilient support arranged to move a mattress to be beaten into and out of operative relation with said beating elements; and means for preventing withdrawal of said support while said beating elements are in operation.

22. A mattress beating machine comprising a frame; a lower beating element rigidly secured in the lower portion of said frame; a resilient rotatable mattress support slidably mounted within the frame and arranged to support a mattress above the lower beating elements whereby both upper and lower sides of said mattress may be exposed to the action of said upper and a lower beating elements; an upper beating element mounted 100

for vertical movement within the frame and above the mattress support; means for moving the said upper beating elements relatively to the mattress; means for operating either beating element independently of the other; and means for preventing operation of the lower beating element while the mattress support is out of operative position relative to the beating elements and for preventing withdrawal of the mattress support from said operative position while said lower beating elements are operating.

23. A mattress beating machine comprising a suitable frame; a lower beating element mounted within the lower portion of said frame vertically disposed threaded rods mounted within the upper portion of said frame; an upper beating element mounted upon the threaded rods whereby said upper element may be adjusted vertically when said threads are rotated; a rotatable resilient mattress support slidably mounted upon the frame and between the upper and lower beating elements and arranged to support a mattress to expose both sides thereof simultaneously to the action of said upper and lower beating elements; means for operating either beating element independently of the other; means for rotating the vertically disposed threaded rods to adjust the upper beating elements relatively to the mattress; means for preventing operation of the lower beating element when the mattress support is out of operative position relatively to said lower beating element; and stripping means for stripping the mattress from the upper beating element.

24. A mattress beating machine comprising a suitable frame; a lower beating element mounted within the lower portion of said frame; vertically disposed threaded rods mounted within the upper portion of said frame; an upper beating element mounted upon the threaded rods whereby said upper element may be adjusted vertically when said threads are rotated; a rotatable resilient mattress support slidably mounted upon the frame and between the upper and lower beating elements and arranged to support a mattress to expose both sides thereof simultaneously to the action of said upper and lower beating elements; means for operating either beating element independently of the other; means for rotating the vertically disposed threaded rods to adjust the upper beating element relatively to the mattress; means for preventing operation of the lower beating element when the mattress support is out of operative position relatively to said lower beating element; and stripping means for stripping the mattress from the upper beating element; and lofting means for lofting the mattress when the upper beating element only is being operated.

25. The combination with a mattress beat-

ing machine comprising a resilient support arranged to support a mattress to expose both sides thereof simultaneously to beating elements, of upper and lower beating elements comprising a plurality of parallel rods, the rods of one beating element being alternately positioned in respect to the position of the rods of the other beating element whereby a mattress beaten simultaneously by both sets of beating elements will be corrugated repeatedly to effect a uniform distribution of stuffing within said mattress.

26. A mattress beating machine comprising a resilient rotatable support arranged to support a mattress to expose both sides thereof simultaneously to the action of beating elements; and beating elements arranged on both sides of said mattress and arranged to beat the same, said beating elements comprising parallel bars, the bars of one element being arranged alternately with the bars of the other element whereby a mattress on said support will be corrugated successively to effect a uniform distribution of stuffing within the mattress into the corners and edges thereof when beaten by said elements and rotated by said support while being beaten.

27. A mattress beating machine comprising a resilient support arranged to support a mattress to expose both sides thereof simultaneously to the action of beating elements; beating elements arranged on both sides of said support and mattress thereon, said elements comprising parallel bars arranged alternately on opposite elements whereby a mattress may be corrugated successively during the beating process to uniformly distribute stuffing within the mattress; means for operating either beating element independently of the other; and lofting means comprising parallel supporting bars arranged alternately with the bars of one element and opposite the bars of the opposite element, each successive inner bar being arranged farther from the mattress at the center than the adjacent outer bar whereby the support thus afforded will be farther from said mattress at the center than at the edges of said mattress whereby said mattress may be lofted to loft stuffing toward the center of the mattress when the bars of the opposite beating element only are being operated.

28. A mattress beating machine comprising upper and lower beating elements comprising parallel bars, the bars of the upper element being positioned alternately with respect to the bars of the lower beating element; means for operating either beating element independently of the other element; a resilient mattress support arranged between the beating elements and adapted to simultaneously expose both sides of a mattress thereon to the action of said beating

elements; a stripping means arranged between the bars of the upper element and arranged to strip the mattress therefrom; and a lofting means comprising arcuate parallel bars arranged below the support and between the bars of the lower beating element said bars increasing in distance from the mattress toward the center thereof whereby

a greater rebound may be imparted by the resilient support to the mattress thereon 10 when beaten by the upper beating element only to loft the stuffing within said mattress.

In witness whereof I hereunto set my signature.

JOSEPH W. DROLL.
